UNITED STATES PATENT OFFICE

156,446

BUNTING OR THE LIKE

Irving Lustgarten, New York, N. Y.

Application April 7, 1948, Serial No. 145,573

Term of patent 14 years

(Cl. D92—2)

To all whom it may concern:

Be it known that I, Irving Lustgarten, a citizen of the United States of America, residing in New York, county of New York, and State of New York, have invented a new, original, and ornamental Design for a Bunting or the like, of which the following is a specification, reference being had to the accompanying drawing, forming part thereof,

Fig. 1 is a front view of a bunting or the like, showing my new design.

Fig. 2 is a rear view thereof.

Fig. 3 is a plan view thereof as it appears in open position and showing the lining partially detached.

I claim:

The ornamental design for a bunting or the like, substantially as shown and described.

IRVING LUSTGARTEN.
